TAPE WINDING MACHINE

Application filed November 15, 1928. Serial No. 319,709.

The invention relates to machines for winding tape on various objects such as electrical coils.

In the manufacture of many types of coils the wire is wound on a mandrel or former and removed therefrom when the winding is finished, thereby forming marginal coils or coils with openings in them. Tape is generally wrapped or wound about the several 10 turns of wire either fully around the coil or at selected points thereon. Since the coil is closed it is necessary to pass the tape through the opening in the coil for each turn of the tape about the wires. Heretofore most winding of tape upon closed coils has been done by hand.

The object of our invention is to provide a simple machine which is capable of efficiently and rapidly winding a tape about the turns 20 of the wire of a coil.

The invention is illustrated in the accompanying drawings in which

Figure 1 is a central vertical cross-section of the machine; Fig. 2 an end view of the 25 same; Fig. 3 a plan view of the same; Fig. 4 a cross-section on line 4—4 of Fig. 1; Fig. 5 a plan view of the detachable link; Fig. 6 a side view of said link; Fig. 7 a plan view of the tape-receiving link and Fig. 8 a side 30 view of the latter link.

In the illustrative embodiment of the invention 1 represents the frame of the machine, the lower portion being open on one side and adapted to be closed by the removable plate 2. Shafts 3, 4, and 5 are mounted at one end in the fixed side 6 of the frame the opposite ends of the shafts having suitable mountings in the plate 2. A pinion 7 is keyed to the shaft 3, which shaft is driven by 35 suitable power means. The pinion 7 meshes with two double gears 8 and 9 that are mounted upon the shafts 4 and 5 respectively. The teeth of the gears project through slots 10 and 11 formed in the concaved partition 12 formed on the frame above the shafts 4 and 5. Guards 13 and 14 project inwardly from 40 the side 6 and the plate 2. The guards are spaced from the partition 12 and curve longitudinally similarly to the partition. The

partition and guards form a track for the tape carrier 15.

The upper portion of the frame consists of a standard 16 suitably secured to the base and carrying at its upper end a head 17 having a 55 track 18 on its lower side corresponding to the track formed by the partition 12 and guards 13 and 14 and adapted to support the tape carrier 15.

The tape carrier 15 is composed of a series 60 of links 19 each of which consists of a curved plate 20 bifurcated at one end and having two parallel upstanding walls 21 at its opposite sides. Teeth 21^a are formed along the upper edge of each wall and are adapted to be engaged by the teeth of the gears 8 and 9. A tongue 22 at the opposite end of each plate 20 is adapted to be received by the bifurcated end of another such plate and pivoted thereto by a pin 23 thereby making possible the 70 forming of a link belt or carrier. The tongue on one of the links 24 is hook shaped so that the hook 25 will removably engage the pin in the bifurcated end of the adjacent link in order that the belt may be separated or opened 75 at said link for insertion of the belt through the coil 26 that is to be taped. Each of the links carries rollers 27 inserted in openings formed in the plate 20.

The link 28, Figs. 7 and 8, differs from the 80 other links in that a central opening 29 is formed in the plate 20^a and rollers 30 are mounted in the opening in spaced relation.

An opening 31 is formed in the standard 16 and rollers 32 are mounted in the opening. 85 The tape T is led from the spool 33 through the opening 31 and through the opening 29 in the link 28, the free end of the tape being secured to the coil. The belt is driven counterclockwise (Fig. 1) and as the link 28 90 passes downwardly through the coil and upwardly exteriorly of the coil it carries the tape with it and wraps or winds the tape upon the coil. The coil is held by the operator upon an apertured shelf 34 and he rotates it on the shelf to cause the tape to be wound spirally upon the coil.

The shelf 34 is mounted on a rack 35 that is 95 longitudinally movably supported on the frame, a pawl 36 being adapted to engage the

rack at any adjusted height and hold it and the shelf in such position.

A band 37 is secured at one end to the partition 12 and is disposed between the side walls 5 of the links. This band projects through a slot 38 formed in the wall of the frame 1 and its projecting end is suitably attached to a treadle 39. The anchored end of the band and the slot 38 are both adjacent the opposite 10 ends of the track in the lower portion of the frame 1 hence when the treadle is depressed the band is drawn against the bottom plates of the links and retards or checks the movement of the belt. The band is therefore a 15 brake to retard or stop the belt when necessary.

A shaft 40 is suitably mounted in the brackets 41 that project from the frame 1, and upon this shaft are pivoted two cylinders 42. In each cylinder there is a spring 43 engaging at its lower end the head of a bolt 44, and at its other end the spring engages the upper end of the cylinder. The bolt extends through the upper end of the 25 cylinder and passes through a lever 45; the nut 46 securing the bolt to the lever. The levers 45 are pinned to a rock shaft 47 that is revolutely mounted on the standard 16. A lever 48 is secured to the shaft 47 between 30 the levers 45 and projects through a slot 49 in the standard into a recess 50 formed in the head 17, which latter lever under the influence of the springs 43 supports the head and holds it against the adjusting screw 51, 35 which screw is adjusted in accordance with the desired tightness of the belt.

Another lever 52 is secured to the rock shaft 47 and a rod or cable 53 is attached to the free end of the lever 52 and depends for convenient access by the operator. By pulling down on the rod or cable 53 the shaft 47 opposed by the springs 43, is rocked to cause the lever 48 to lower the head 17 and thereby loosen the belt so that the link 24 may be detached from its neighbor. Upon releasing the rod or cable the springs 43 cause the head 17 to return to its uppermost position. A guard 54 is vertically slidably mounted in the head 17 which, when lowered, protects the 50 operator from contacting with the moving belt and also tends to retain the outer fold of the tape in the channel of the belt as it is drawn through the coil 26 and thereby prevent looping of the tape.

55 What we claim is:

1. In a tape winding machine, a frame, a track formed on the frame, an endless carrier slidable on the track, a head slidably mounted on the frame and having a track 60 slidably supporting the carrier, resilient means opposing the movement of the head to maintain tension on the carrier, means to move the head to release the said tension, means to drive the carrier, means to support 65 the object to be taped in the path of the car-

rier and a spool of tape, the free end of the tape being extended through the carrier for attachment to the object.

2. In a tape winding machine, a frame, an arcuate track formed on the frame, a head 70 slidably mounted on the frame and having an arcuate track thereon, an endless link belt slidably mounted on both tracks, means to drive the belt, means to support an object to be taped in the path of the carrier, a spool of tape the free end of the tape being extended through one of the links of the belt for attachment to the object, a rock shaft mounted on the frame, a lever secured to the shaft and engaging the head, a second lever secured to the shaft and a spring opposed member connected to the latter lever and adapted to cause the head to move in one direction for placing tension on the belt and means to cause the head to move in the opposite direction.

80 In witness whereof we have hereunto subscribed our names.

GUSTAV W. FRIES.

FRANK W. FINKHOUSEN.
